M. DONAUER.
LIQUID AGITATING TANK MECHANISM.
FILED JULY 1, 1920.

UNITED STATES PATENT OFFICE.

MAX DONAUER, OF ELYRIA, OHIO, ASSIGNOR TO THE ELYRIA ENAMELED PRODUCTS COMPANY, OF ELYRIA, OHIO, A CORPORATION OF OHIO.

LIQUID-AGITATING-TANK MECHANISM.

Application filed July 1, 1920. Serial No. 393,432.

To all whom it may concern:

Be it known that I, MAX DONAUER, a citizen of the United States, residing at Elyria, in the county of Lorain and State of Ohio, have invented certain new and useful Improvements in Liquid - Agitating - Tank Mechanisms, of which the following is a full, clear, and exact description, such as will enable others skilled in the art to which 10 my invention appertains to make and use the same.

My invention relates to liquid agitating tank mechanisms and particularly to such mechanisms as employ a propeller in a tank, 15 to produce agitation of the liquid contents of the tank.

It is an object of my invention to promote such agitation as will accomplish the results sought, in an apparatus simple of construction, inexpensive to manufacture, and sanitary in its effect upon processed food products. It is a further object of my invention to promote the aforesaid objects in a device from which the peripheral flow of liquid 25 from the tips of the propeller blades is avoided, as I find that in case of some liquids sought to be processed I get a superior result when liquid is propelled from the propeller in a stream at a moderate rate of speed. Other objects of my invention and 30 the invention itself will be better understood by reference to the drawings accompanying this specification, and in which drawings.

Figure 1 shows an embodiment of my invention shown mostly in cross section.

Figure 2 shows a plan view of the tank mechanism of Figure 1, the view of Figure 1 being taken on a line I—I of Figure 2.

Referring to the drawings, at A—A are 40 shown curved side walls of a tank herein illustrated as cylindrical, and at B, is shown the bottom wall thereof, herein shown as downwardly curved. Near the bottom wall of the tank, I perforate the side wall at a 45 point C to admit a propeller shaft D having on the end inside the tank a propeller E. Mounted on the opposite end of the shaft, outside the tank, is provided a pulley P, by means of which, from a suitable source of 50 power, power may be communicated to the propeller shaft to rotate the said propeller. The propeller is preferably located relatively near the adjacent side wall, the distance from the adjacent side wall being such 55 as to permit a flow of current from or into

the propeller through the said space, depending on the direction of rotation of the said propeller.

Around the said propeller and preferably carried on the tips of the blades thereof, 60 is mounted a metallic cylinder F, for a purpose later to be made apparent.

When the propeller is rotated, the liquid contents of the tank are caused to travel through the cylinder F and against the opposite side wall of the tank, being deflected 65 thereby in all directions.

The tendency of the liquid contents of the tank to rotate as a whole is very much restricted by the presence of the cylinder F, 70 which also restricts the tendency of the propeller to throw off particles of the liquid peripherally. In this way a greater flow of current is had traveling parallel with the axis of rotation of the propeller shaft, said 75 flow being of considerable strength, though of moderate velocity as compared with the peripherally flung currents, which otherwise might be had in other constructions; also the tendency of the propeller to set up 80 a rotary motion of the tank contents, about an axis constituting an extension of the propeller shaft, is not so great.

Having thus described my invention in a particular embodiment, I wish it to be understood that I do not limit my invention to it, but am aware that numerous and extensive departures may be made from the embodiment herein illustrated and described and without departing from the spirit of my 90 invention.

I claim:

1. In a device of the class described, a substantially cylindrical tank the axis of the said tank being disposed vertically, a rotatable pitched propeller located in the said tank and near the bottom thereof, said propeller having an enclosing casing around its periphery, said propeller being adapted to rotate in a vertical plane, the axis of rotation being directed substantially toward the vertical axis of the tank.

2. In a device of the class described, a substantially cylindrical tank the axis of the said tank being disposed vertically, a rotatable pitched propeller located in the said tank and near the bottom thereof, said tank having curved side walls, and said propeller having an enclosing casing around its periphery, said propeller being adapted 105 110

to rotate in a vertical plane, the axis of rotation being directed substantially toward the vertical axis of the tank.

3. In a device of the class described, a substantially cylindrical tank the axis of the said tank being disposed vertically, a rotatable pitched propeller located in the said tank and near the bottom thereof, said tank having cylindrical side walls, and said propeller having an enclosing casing around its periphery, said propeller being adapted to rotate in a vertical plane, the axis of rotation being directed substantially toward the vertical axis of the tank.

4. In a device of the class described, a substantially cylindrical tank the axis of the said tank being disposed vertically, a rotatable pitched propeller located in the said tank and near the bottom thereof, said tank having an inclined bottom wall, and said propeller having an enclosing casing around its periphery, said propeller being adapted to rotate in a vertical plane, the axis of rotation being directed substantially toward the vertical axis of the tank.

5. In a device of the class described, a substantially cylindrical tank the axis of the said tank being disposed vertically, a rotatable pitched propeller located in the said tank and near the bottom thereof, said tank having a downwardly inclined bottom wall, and said propeller having an enclosing casing around its periphery, said propeller being adapted to rotate in a vertical plane, the axis of rotation being directed substantially toward the vertical axis of the tank.

6. In a device of the class described, a substantially cylindrical tank the axis of

the said tank being disposed vertically, a rotatable pitched propeller located in the said tank and near the bottom thereof, said tank having curved side walls, said tank having an inclined bottom wall, and said propeller having an enclosing casing around its periphery, said propeller being adapted to rotate in a vertical plane, the axis of rotation being directed substantially toward the vertical axis of the tank.

7. In a device of the class described, a substantially cylindrical tank the axis of the said tank being disposed vertically, a rotatable pitched propeller located in the said tank and near the bottom thereof, said tank having cylindrical side walls, said tank having an inclined bottom wall, and said propeller having an enclosing casing around its periphery, said propeller being adapted to rotate in a vertical plane, the axis of rotation being directed substantially toward the vertical axis of the tank.

8. In a device of the class described, a substantially cylindrical tank the axis of the said tank being disposed vertically, a rotatable pitched propeller located in the said tank and near the bottom thereof, said tank having cylindrical side walls, said tank having a downwardly inclined bottom wall, and said propeller having an enclosing casing around its periphery, said propeller being adapted to rotate in a vertical plane, the axis of rotation being directed substantially toward the vertical axis of the tank.

In witness whereof, I have hereunto signed my name this 25 of June, 1920.

MAX DONAUER.
